UNITED STATES PATENT OFFICE.

NEIL F. HAVENS, OF ALEXANDRIA, VIRGINIA.

HOISTING MECHANISM.

1,312,115.

Specification of Letters Patent. Patented Aug. 5, 1919.

Application filed February 2, 1918. Serial No. 215,111.

To all whom it may concern:

Be it known that I, NEIL F. HAVENS, a citizen of the United States, and a resident of Alexandria, in the county of Alexandria, 5 and State of Virginia, have invented a certain new and useful Improvement in Hoisting Mechanism, of which the following is a specification.

My present invention relates to hoisting mechanism, and particularly to a mechanism to be fitted to and used upon a motor truck of standard type and construction.

An object of my invention is to arrange for derivation of operating power from the 15 power means of the motor truck.

A further object is to provide a drive for the hoisting means in which the power transmitting shaft is disposed substantially at right angles to the turning axis of the hoisting drums.

Another purpose lies in mounting the hoisting structure upon a supporting frame which can be removed from the truck frame to leave the same free of obstructions, and 25 in mounting an upright frame and a boom in such relation that these parts can be lowered for movement of the machine and can be removed when desired.

A still further object is to provide side 30 brace arms having raising jacks carried at the ends thereof, which arms can be swung out and then have the jacks thereof turned down to accomplish a side support for the frame to hold against lateral twisting or 35 tilting, and to so mount the braces that when not in use they can be folded in against the truck frame.

Yet another object is to provide and arrange novel mounting and brace means for 40 the several parts.

Further objects of my invention will appear in the following detailed description, taken in connection with the accompanying drawings, forming a part of this specification, and in which drawings:

Figure 1 is a view in elevation of the rear portion of a motor truck of standard construction showing the device of my invention applied thereon.

Fig. 2 is a plan view of the parts as shown in Fig. 1.

Fig. 3 is a detail view with the truck frame sectioned transversely to better disclose the arrangement and mounting of the boom supporting frame and parts associated therewith.

Fig. 4 is an enlarged detail view to disclose the driving connection from the power means of the truck to the hoisting mechanism.

Fig. 5 is a detail perspective view showing the construction of the foot bearings for the boom supporting or upright frame.

In the drawings, where similar characters refer to similar parts throughout the views, 65 A designates the truck frame as an entirety, the hoist supporting frame B being shown as mounted thereon, and the hoisting structure being shown at C. The upright frame D is mounted preferably at a point that the 70 weight carried thereby will be centralized upon the load springs of the rear wheels of the truck, and the boom E is mounted from and supported by this frame. The lateral brace arms F and G are preferably disposed 75 adjacent the mounting of the upright frame D, as it is at this point that the greatest twisting force will be exerted upon the vehicle frame, and it will of course be understood that the several parts are mounted and 80 supported in any suitable manner. Power transmission to the hoisting structure is accomplished from the vehicle transmission, generally indicated at H, in a manner to be hereinafter more fully set forth.

85 The supporting frame B has the hoisting mechanism mounted thereon, and this hoisting mechanism can in fact be of any desired form and construction, winding drums 1 and 2, and boom swinging drums 3 and 4 being 90 included. A hoist operating shaft 5 is mounted in suitable bearings and is geared to operate the winding drums 1 and 2 and the shaft by which the boom swinging drums 3 and 4 are turned, and this shaft 5 has a 95 beveled gear 6 thereon. The frame B is secured on the truck frame A by means of screws 7, or any other suitable means of fastening, and a power transmission shaft 8 is mounted to extend substantially parallel 100 with the main shaft of the truck, a beveled gear 9 being mounted on the shaft in mesh with the beveled gear 6 so as the power transmission shaft 8 is turned, the hoist operating shaft 5 will be revolved at substantially the 105 same speed.

The "Mack" truck and some trucks of other makes, have a stub shaft 10 extending from the transmission and revolving on an axis substantially parallel with the main 110 shaft of the truck, and as has been stated above, it is the purpose of my invention to

accomplish a drive from this stub shaft or from a standard part of a vehicle as already in use.

A drive shaft 11 is connected by a shaft 5 coupling 12, with the stub shaft 10, and at its remaining end is mounted in a bearing 13 provided on the truck frame, and thus as the truck engine is in operation this shaft 11 will be turned. A sprocket wheel 14 is 10 mounted on the shaft 11, and a sprocket 15 is secured on the shaft 8 to line up with the sprocket 14, a sprocket chain 16 being arranged to accomplish a driving connection from the one sprocket to the other. Through 15 the driving connection thus established, the power transmission shaft 8 will impart constant revoluble movement to the hoist operating shaft 5 during operation of the truck engine, and when the operating levers 20 20 are shifted to throw the clutches of the drums into operative connection, the respective drums will be revolved. As has been stated, the frame B is secured on the truck frame A by the use of bolts 7 or other separable fastenings, and thus the frame is 25 removably secured in place. As the shaft 8 is carried by the frame portion B and the shaft 11 is supported from the truck frame A, it is only necessary to separate one of the 30 links of the chain 16, in removal of the frame B, and then the hoisting structure as an entirety will be detached from the truck frame and the only part remaining will be the shaft 11, the coupling 12, bearing 13, and 35 sprocket wheel 14, however, as these parts are located below the top of the frame they will not offer obstruction or in any way interfere with the use of the truck.

The upright frame D is made substantially A-shaped, and includes the side members 18 and 19 and the cross bar 20. Bearing portions 21 and 22 are secured on the lower ends of the side members 18 and 19, and bearing members 23 and 24, the construction of which is best shown in Fig. 5, are mounted on the side bars of the truck frame at points substantially above the rear axle, the bolts 25 being provided to mount the bearing portions 21 and 22 pivotally 45 within the bearing members 23 and 24. By this mounting of the upright frame structure, this frame structure can be swung down rearwardly to rest upon the truck frame A, but the closed ends of the bearing members 23 and 24 limit movement of the same when it has been swung up to the upright relation and guard against forward swinging of this upright frame. To support the frame portion D in the position for 50 use the braces 26 and 27 are connected at the upper end thereof and are then extended downwardly and forwardly to terminate adjacent the truck frame A, where they are removably secured by bolts or other fastenings 28. When the upright frame struc-

ture is raised and the braces 26 and 27 are secured to the truck frame, the parts will be supported in substantially the position shown by the full lines of Fig. 1, but by removal of the bolts or fastenings 28, the 70 frame structure D and the brace members 26 and 27 will fold to the position indicated by the dotted lines, or if the frame B and the structure carried thereby be removed, then the brace members 26 and 27 will fold 75 down substantially flat against the truck frame. A cross bar 29 is mounted between the side bars of the truck frame, and a step-bearing member 30 is mounted substantially centrally upon this cross bar, the cable 80 wheels 31 and 32 being mounted in conjunction with the step-bearing member. An upright 33 is provided with bearing extension 34 at its lower end and at its upper end has a cap 35 mounted, this cap being provided with a bearing extension which lines up with the extension 34. The length of the upright is so gaged that when the bearing extension 34 is placed within the step-bearing opening, the extension of the cap 35 is 85 adjacent the cross bar 20, and a bearing 36 is provided. The bearing 36 is provided for reception of the bearing extension of the cap 35, bolts 37 being provided to removably secure this bearing 36 upon the cross bar 20. 90 At the lower end of the upright 33, a bull wheel 38 is provided, this wheel being grooved for reception of a cable extending from the boom swinging drums 3 and 4, and a socket 39 is provided for reception of 100 the foot of the boom E. Cable wheels 40 and 41 are revolubly mounted adjacent the upper end of the upright 33 and are substantially in line with the cable wheels 31 and 32 as carried by the step-bearing member 30. 105

As has been stated, the boom E has the foot end thereof placed within the socket opening 39 formed or provided at the lower end of the upright 33, and a brace member 42 is connected from the outer end of the boom E to an eyelet 43 at the upper end of the frame D, the boom E being thus held in angular disposition as shown in Fig. 1. Cables 44 are extended from the winding drums 1 and 2 over the cable wheels as carried by the upright 33 and by the step-bearing member 30, and then led up adjacent the boom and over cable wheels 45, these cables having the hooks 46 associated therewith for attachment of a load. By moving 110 the operating levers 17, the winding drums will be connected to be turned by the power connection from the stub shaft 10, and in consequence the cable attached thereto will be drawn in, it of course being understood that this operation will be carried out as in 115 the case of ordinary hoisting mechanism. The boom will also be swung in the usual manner, by setting the parts for turning of the drums 3 and 4 in one direction or the 120 125 130

other to consequently swing the upright 33 through the connection of the bull wheel 38 therewith.

When the parts as carried at the rear of the 5 truck frame are to be removed from the truck or are to be folded down to reduce the height of the mechanism so that the truck may be more readily transported or driven from one point to another, the boom 10 E may be removed, following which the bolts 37 are withdrawn to release the bearing 36. When the bearing has been loosened, the upright 33 together with the bull wheel 38 can be removed by lifting the bearing 15 extension 34 from the bearing opening of the step-bearing member 30, and then by loosening the bolts or fastenings at 28, the upright frame D is left free to be swung down to the position indicated by the dotted 20 lines of Fig. 1, or by removing the bolts 25, this upright frame D together with the brace members 26 and 27 can be entirely removed from the connection with the truck 25 frame.

Under some circumstances, as where the 30 hoisting mechanism is to be moved only a short distance, it may be desirable to leave the boom in substantially its normal foot- 35 ing, and to support the boom together with a bucket or tackle carried therefrom upon a trailer. Where this is done, it is not necessary to remove or unstring any of the hoisting cables or other tackle, and at the same time the boom can be lowered to rest upon 40 the frame and the upright frame structure D can then be folded. The bull wheel and the upright carried therewith will of course be retained in the mounting as shown, and when it is desired to again set up the parts 45 for use, this can be done by manually raising the frame D, or by raising the same with a block and tackle.

While the parts as hereinbefore described can be used with very efficient results, and in practically all connections, due to the fact that the boom E has the outer end thereof extended to be disposed at quite some distance from the upright 33, when the boom has been swung to one side or the 50 other of the truck frame A and a load is caught by the hook 46, the leverage secured upon the frame will cause the same to be twisted and raised at one side, and undue strain will be placed upon the load springs, 55 to overcome which tendency the side brace members F and G are provided. Bearing members 47 and 48 are mounted on the sides of the truck frame A in the rear of the mounting of the bearings 23 and 24 by 60 which the upright frame D is mounted, and the side brace members F and G are pivotally mounted in these bearings 47 and 48 by bolts or pivot pins 49, the arrangement of the parts being such that the members F 65 and G can be swung out to the full line

position of Fig. 2, or can be folded in to be disposed adjacent the sides of the frame A, as indicated by the dotted lines. Jackscrews 50 are mounted at the ends of the brace members F and G, and at their lower 70 ends have plates 51, handles 52 being provided at the upper end of the jackscrews. By this arrangement of the parts, the brace members F and G can be swung to extend substantially at right angles from the sides 75 of the truck frame A, further movement being stopped by contact with the closed ends of the bearing members 47 and 48. The jackscrews 50 will then be tightened down to bring the bearing plates 51 thereof into 80 proper bearing engagement upon the ground or on the surface on which the motor truck is supported, or blocks will be used, and thus the truck frame will be securely braced against lateral twisting movement, and additional support will be provided for the frame to thus take a part of the load placed 85 thereon.

The use and operation of the parts has 90 been somewhat fully set forth as the description has progressed, and it is therefore not thought that I need here to go into further detail in this respect. Changes in details may be made without departing 95 from the spirit or scope of my invention; but,

I claim:

1. In a hoisting device, the combination with an ordinary motor truck including a chassis having side rails, of a supporting 100 frame removably mounted upon said chassis, a boom detachably carried by said chassis, a hoisting mechanism carried by said supporting frame, bearing members carried by said side rails, bracing means for said boom 105 adapted to be detachably connected to said bearing members, whereby the hoisting mechanism, boom and bracing members may be removed from connection with said truck.

2. In a hoisting device, the combination 110 with an ordinary motor truck including a chassis having side rails, of a supporting frame removably mounted upon said chassis, a boom pivotally and detachably connected to said chassis, a hoisting mechanism carried 115 by said supporting frame, bearing members carried by said side rails, bracing means for said boom adapted to be detachably connected to said bearing members, whereby the hoisting mechanism, boom and bracing 120 members may be removed from connection with said truck, said bracing means being pivotally connected to said bearing members to permit the bracing means to be folded to lie flat upon the truck frame, and stay rods 125 pivotally connected to the free end of said bracing means and adapted for detachable connection with said side rails.

3. In a hoisting device, the combination with a motor truck including a chassis hav- 130

- ing side rails, of socket bearing members attached to said side rails and comprising flat attaching portions, upstanding side flanges and upstanding end flanges connected to said side flanges to form a socket, a substantially A-shaped upright frame, bearing portions upon the lower end of the sides of said frame and comprising relatively thin depending portion, said depending portion pivotally connected to said side flanges and adapted to engage said end flanges to limit pivotal movement of the A-shaped frame in one direction.
4. In a hoisting device, the combination with a motor truck including a chassis having side rails, of socket bearing members attached to said side rails and comprising flat attaching portions, upstanding side flanges and upstanding end flanges connected to said side flanges to form a socket, a substantially A-shaped upright frame, bearing portions upon the lower end of the sides of said frame and comprising relatively thin depending portion, said depending portion pivotally connected to said side flanges and adapted to engage said end flanges to limit pivotal movement of the A-shaped frame in one direction, and braces attached to the upper end of the side members of said frame and adapted for connection with said truck frame to hold the upright frame against pivotal movement.
5. In a hoisting device, the combination, with a motor truck including a chassis having side rails, of a substantially A-shaped upright frame, means pivotally and detachably connecting said A-shaped upright frame to said side rails, a thrust bearing carried by the truck frame, an upright having its lower end journaled in said thrust bearing
- and its upper end rotatably connected to the cross bar of said A-shaped upright frame, a boom connected to said upright, cable guiding wheels carried by said thrust bearing, and cable guiding wheels carried by said upright and in alinement with the bearing carried cable guiding wheels.
6. In a hoisting device, the combination with a motor truck including a chassis having side rails, of bearing members carried by said side rails and comprising flat attaching portion, upstanding side flanges and upstanding end flanges connected to said side flanges to form a socket, a substantially A-shaped upright frame, bearing portions upon the lower end of the sides of said frame comprising relatively thin depending portions, said depending portions pivotally connected to said side flanges and adapted to engage said end flanges to limit pivotal movement of the frame in one direction, braces attached to the upper end of said side member and adapted for connection with the side rails of said chassis to hold the upright frame against pivotal movement, a thrust bearing carried by the thrust frame, an upright having its lower end journaled in said thrust bearing and its upper end rotatably connected to the cross bar of said A-shaped upright frame, a boom connected to said upright, cable guiding wheels carried by said thrust bearing, cable guiding wheels carried by said upright frame and in alinement with the bearing carried cable guiding wheels, and a cable guiding wheel carried by said boom and adapted for coaction with said former mention guiding wheel to guide a hoisting cable.

NEIL F. HAVENS.
